WITNESS:

Victor J. Evans

ATTORNEY

UNITED STATES PATENT OFFICE

AXEL G. HILDEBRAND, OF BROOKLYN, NEW YORK

EJECTOR PACKAGE

Application filed July 19, 1930. Serial No. 469,170.

The object of this invention, is to provide a container, particularly adapted for medical tablets which may be of such size as to adapt it to be conveniently carried in the pocket of 5 the user, which is so constructed as to permit a single tablet being easily removed without in anyways interfering with the remaining tablets, which shall be cheap in manufacture, positive in action, easily refilled and which 10 shall be practically dust and moisture proof so that the contents are retained in a sanitary condition and without liability of undue deterioration.

To the attainment of the foregoing the invention consists in the improvement herein- 15 after described and definitely claimed.

In the drawing:

Figure 1 is a perspective view of one form 20 of the improvement.

Figure 2 is an approximately central trans- 25 verse sectional view therethrough.

Figure 3 is a somewhat enlarged sectional 30 view approximately on the line 3-3 of Figure 2.

Figure 4 is a similar sectional view through 35 a slight modification with the ejector removed.

Figure 5 is a side elevation thereof.

Figure 6 is an edge view with the parts 40 constituting the case separated.

The improvement is preferably constructed 45 of metal but, of course, may be of other material. The device comprises a substantially cylindrical body 1 that is formed with a mouth extension. The sides of the mouth extension are parallel with the sides of the body and the end walls of the mouth are inwardly rounded, as at 2.

The cylindrical body 1, as well as the mouth of the improvement is formed of two parts, the body portions of the improvement being fluted to provide an interengaging tongue 3 and a groove 4. The section of the body formed with the tongue 3 is extended 50 therebeyond so that the edge of the said section will contact with the inner face or side of the cooperating section.

The sides of the mouth portion of the body 55 are preferably bulged outwardly at diamet- rically opposed corners to receive therein

trunnions 5 that are centrally formed upon the sides of a disc or wheel that provides the ejector 6. The ejector may be made in two parts if desired and the ejector is peripheral- 55 ly provided with diametrically opposed notches 7. The mouth portion of the device may be spread to remove the ejector 6 there- 60 from, for the filling or refilling of the body but preferably a single medical tablet 8 is received in each of the notches as the ejector is turned on its trunnions so that the body is thus filled with the tablets. The turning of the ejector after the body is filled with medical tablets such tablets will be singly de- 65 livered from the body.

In Figures 4, 5 and 6 of the drawing the device is slightly modified. The body is of cylindrical formation and is constructed of two parts or sections. One of the sections 70 9 has its open edge formed with an offset extension 10 to receive therein an annular flange 12 formed on the open edge of the sec- 75 ond body section 13. From the rounded portion the sections 9 and 13 have their sides extended and their edges formed with con- 80 caved extensions 14. When the sections are as- 85 sembled the flange 12 is received over the flange 10 and the flange 10 is then bent over the flange 12. Thus the sections 9 and 13 are connected together by an interengaging tongue and groove. The sides of the mouth 90 have diametrically opposed outwardly bulged portions 15 and the said sides from their outer edges are formed with depressions 16 that communicate with the outwardly bulged por- 95 tions 15. The depressions serve as guides for the trunnions 17 for the disc ejector 18, the latter being provided with opposed notches similar to those in the ejector 6. By 100 this construction the mouth may have its sides sprung away from each other so that the ejector can be readily removed therefrom when filling the bottle and likewise the trunnions of the ejector can easily pass through the guide depressions and be received in the outwardly bulged portions or sockets 15. In both instances the major portion of the ejector is received in the mouth of the body so that the projecting portion thereof can be readily gripped by the finger of the op-

erator and turned to singly eject the medical tablets 8 as disclosed by Figure 1 of the drawing.

It is thought the foregoing description when read in connection with the accompanying drawing will fully and clearly set forth the construction and advantages of the improvement to those skilled in the art so that further description will not be required.

10 It will be noted that the device is of a size so that the same can be easily and conveniently carried in the pocket of the user, that the device provides no sharpened edges which injure the user's pocket; that the ejector fully

15 covers the mouth of the body and consequently the tablets are retained in a sanitary condition and are practically proof against dust or moisture.

Having described the invention, I claim:

20 A tablet container comprising a cylindrical body consisting of side sections having flanges adapted to overlap and frictionally engage each other, said sections being substantially the same shape and dimensions,

25 the body being provided at one side edge with an arcuate mouth having side depressions, a disk journaled concentrically in said mouth and provided with peripheral notches and having side projections entering said depressions, a peripheral portion of the disk entering the body of the container and a peripheral portion of the disk being disposed beyond the edge of the mouth.

In testimony whereof I affix my signature.

25 AXEL G. HILDEBRAND.
